UNITED STATES PATENT OFFICE.

WILLIAM F. HODGE, OF NORTH ADAMS, MASSACHUSETTS, AND HARVEY M. GEER, OF BALLSTON SPA, NEW YORK.

STUFFING-BOX FOR VALVES.

SPECIFICATION forming part of Letters Patent No. 589,725, dated September 7, 1897.

Application filed March 17, 1897. Serial No. 628,048. (No model.)

To all whom it may concern:

Be it known that we, WILLIAM F. HODGE, of North Adams, Berkshire county, Massachusetts, and HARVEY M. GEER, of Ballston Spa, Saratoga county, New York, have invented certain new and useful Improvements 5 in Stuffing-Boxes for Valves; and we hereby declare that the following is a full, clear, and exact description thereof, reference being had 10 to the accompanying drawings, which form part of this specification.

This invention is an improvement in stuffing-boxes of valves, especially designed for large valves on water-mains.

15 The object of the invention is to make a packing or stuffing box which is packed or tightened by means of screw-pressure obtained from the screw-threads on the valve-stem itself in connection with elastic packings, and thus may be made perfectly 20 tight at any time to permit the upper ordinary stuffing-box to be packed or repacked without loss of the fluid the passage of which the valve controls and without necessitating 25 the closing or shutting of the valve, thus interrupting the free flow of the fluid.

The primary utility of our invention is to act as an emergency packing of valve-stems of the ordinary water-works gate or valve.

30 Frequently the water-gates of a city or public water-supply develop serious and at all events annoying leakages in the ordinary stuffing-box, and they are generally of such an extent as to require immediate attention.

35 Ordinarily it is a costly thing to excavate to the stuffing-box of these valves and make proper repair. Especially is this true in our northern or winter climates. Further, while said stuffing-box is being repacked the valves

40 as now made must be shut tightly. A fire may occur at that very moment and before the water could be laid on the system again serious damage and loss might occur, especially in the case of a very large valve, which

45 requires hard work and much time to fully open it. Now our invention is designed to obviate these difficulties—to be, in fact, an emergency packing. It is not intended to be in use at all times, but only at such times as

50 it may be felt that the time for repacking the ordinary box has arrived or that we wish to

check further leakage until some convenient time to so repack, and all this can then be done at a minimum of expense and without inconvenience or drawback to the users of 55 the system and without shutting the gate or cutting off the supply.

The invention therefore consists in the novel construction and combination of parts summarized in the claims and hereinafter 60 shown and described.

Referring to the drawings, Figure 1 shows a half-elevation and half-vertical section of an ordinary stop gate or valve for fluids embodying our invention, which only slightly 65 modifies the construction of the casing intermediate the stuffing-box and valve-chamber. Fig. 2 is a section and top view of the elastic packings. Fig. 3 is a section and top view of the hard rings. 70

A designates the casing; B, the sliding gates or valves, hung on the nut C, which is screwed onto the threaded end of the valve-stem D, which has a collar d, working in a cylindrical chamber b in the casing above the valve-chamber, the upper end of chamber b being closed by a removable cap-casting E, which is provided with flanges e, securely bolted to flanges a on the upper end of casing A, as shown. Casting E is also provided with the ordinary 80 stuffing-box F and gland f for packing the stem. 75

The valve-stem D and its collar d are left as generally manufactured, but both above and below collar d, within chamber b, are 85 placed loose hard-metal collars G and loose elastic expansible packing-rings H. The collars G are interposed between collar d, and the rings H are flat on their surfaces fitted against collar d, but are convex or peaked on 90 their surfaces opposite rings H, as shown.

The drawings show the gate fully open, and therefore the stem-collar d, lower loose collar G, and lower loose elastic ring H are then ready for action, and a further slight turning 95 of the stem D in the direction required to open the valve or gate causes the stem-collar d to press on loose collar G, thus expanding the elastic packing-ring H, (lower,) perfectly filling the space between stem, loose collar, 100 and bottom and sides of stuffing-box and making a fluid-tight joint. When valve is

fully closed; then the upper combination G and II similarly come into play or operation by turning the stem D as if to close valve tighter and thus make a fluid-tight joint in the upper section of their stuffing-box. The loose collars G are introduced to prevent wear of the elastic rings by friction of the stem-collar thereon.

The upper packing or stuffing box, as usually found, is retained and will be packed, as usual, with fibrous packing and serve to ordinarily pack the stem.

It will be obvious from the foregoing that in our invention the valve-stem in emergencies can be packed solely by means of the combination of valve-stem, metallic rings, and elastic packing-collars and operated by means of the screw-pressure produced by means of the stem-screw itself.

In applying the invention to old valves without chambers b, or where the employment of the chamber is inadvisable or inconvenient, a collar and ring might be introduced at the point y, so that the valve-stem could be packed when the gate was fully opened.

Having thus described our invention, what we therefore claim as new, and desire to secure by Letters Patent thereon, is—

1. In an emergency packing for valves, the combination of the casing and stem, and a collar on said stem tapered or conical on one side; with a soft elastic and expansible packing surrounding the stem intermediate the ordinary stuffing-box and valves, and adapted to be compressed and expanded simultaneously by the screw action of the valve-stem, all substantially as and for the purpose described.

2. The combination with the casing, valve, and collared valve-stem; of loose metallic collars placed above and below the stem-col-

lar, and elastic packing-rings, above and below said metallic collars, adapted to be packed by means of the pressure of the stem-collar thereon exerted by the screw action of the stem itself after the valve is fully opened or closed, substantially as and for the purpose described.

3. The combination of the casing, having chamber b, the casting E having stuffing-box F and gland f, the valves, and the threaded valve-stem having a collar d within said chamber b; with the hard-metal packing-rings G, G, in said chamber b above and below the collar d, and the elastic packing-rings II in said chamber b above and below the collars G, whereby the valve-stem can be packed, in an emergency, by means of the screw action of the stem exerted on packings G, II, through collar D, after the valves are fully opened or closed, all substantially as and for the purpose described.

4. The combination with the casing, valve and collared valve-stem; of loose metallic collars G, G, having one of its sides tapered or conical, placed above and below the stem-collar, and elastic and expansible packing-rings above and below said metallic collars, adapted to be compressed and expanded simultaneously by means of the pressure of the stem-collar thereon exerted by the screw action of the stem itself after the valve is fully opened or closed, substantially as and for the purpose described.

In testimony that we claim the foregoing as our own we affix our signatures in presence of two witnesses.

WILLIAM F. HODGE.
HARVEY M. GEER.
